UNITED STATES PATENT OFFICE

170,688

RATCHET WRENCH

John N. Gerlach, Santa Ana, Calif.

Application August 16, 1952, Serial No. 21,068

Term of patent 14 years

(Cl. D54—16)

To all whom it may concern:

Be it known that I, John N. Gerlach, a citizen of the United States, residing at the city of Santa Ana, in the county of Orange and State of California, have invented a new, original, and ornamental Design for a Ratchet Wrench, of which the following is a specification, reference being had to the accompanying drawing, forming a part thereof.

Figure 1 is a perspective view of a ratchet wrench, showing my new design.

Figure 2 is a top plan view thereof; and

Figure 3 is an end view thereof.

I claim:

The ornamental design for a ratchet wrench, substantially as shown.

JOHN N. GERLACH.
